UNITED STATES PATENT OFFICE.

ORMOND EDGAR WALL, OF HONOLULU, TERRITORY OF HAWAII.

EXPRESSION DEVICE FOR PLAYER PIANOS.

Application filed February 10, 1921. Serial No. 443,858.

To all whom it may concern:

Be it known that I, ORMOND EDGAR WALL, a citizen of the United States, and a resident of Honolulu, Territory of Hawaii, have invented certain new and useful Improvements in Expression Devices for Player Pianos, of which the following is a specification.

My present invention relates generally to player pianos, and more particularly to expression devices therefor, my object being the provision of a tone control arrangement in which there will be minimum loss of vacuum both in the several adjusted positions as well as during the movement of the parts from one position to another.

A further object is the provision of an expression device in which there is an automatically controlled movement of the parts bringing about either slowly or speedily increasing volume as desired.

A still further object is the provision of an expression device wherein the adjustable moving parts may be locked in various positions upon adjustment thereof and the locked condition retained over a desired period before release.

In carrying out my invention I provide note sheet controlled means located between the usual player or valve chest and its pressure supply means for controlling the pressure supplied to the player or valve chest independent of the supply means and in turn under control of automatically acting means for either sustaining the same in adjusted position or releasing the same for return to normal or any other degree of tension or expression and under control in a somewhat similar manner of means by which to effect either a rapid or a slow increase of volume as desired.

In the accompanying drawings illustrating the preferred form of my invention and constituting a part of this specification,

Figure 1 is a diagrammatic side view illustrating the practical application of my invention.

Figure 2 is a front view, on an enlarged scale, and partly in section, of the pressure control member,

Figure 3 is a detail side view of certain parts shown in Figure 2,

Figure 4 is a horizontal section taken on line 4-4 of Figure 2,

Figure 5 is a diagram illustrating the

means by which control is effected from a note sheet,

Figure 6 is a horizontal sectional view of the means for controlling the extent and speed of movement of the removable parts of the control member, and

Figure 7 is an end view of Figure 6.

Referring now to these figures and particularly to Figure 1 I have shown certain conventional parts of an automatic piano, including a tracker board 10 over which the note sheet 11 passes in operation from the note sheet carrying roll 12 to the take-up roll 13, such movement, as is well known, controlling the passage of air to the primary tubes of which one is seen at 14. The primary tubes lead to a player or valve chest indicated at 15 in Figure 1, which contains valves, the latter controlling communication between its vacuum space and the hammer actuating pneumatics (not shown), through secondary tubes and the like of which one is seen at 16.

I have made no attempt in the present instance to illustrate any particular form of valve arrangement in the player chest 15, as the particular valve arrangement forms no part of my present invention and the invention may be carried out with various forms of valve mechanism and is indeed unlimited in its application except to an action wherein a player chest, having pressure below atmospheric, is utilized.

I have shown the player chest 15 in connection with a reservoir 17 through pipe sections 18 and 19, the former being connected at its upper end to the player chest and the latter being connected at its lower end to the reservoir. The reservoir is subject to suction through a pipe 20 from a pump and the like 21 which may be motor actuated, the motor being seen at 22.

In accordance with my invention the upper end of the pressure supply pipe 19 from reservoir 17 is connected to the base of a control box 23 so as to communicate with the lower interior portion of this box through its base opening 24 as shown in the detail section, Figure 2. This control box has upper, intermediate and lower sections 25, 26 and 27 respectively, a horizontal rigid partition 28 separating the upper and intermediate sections to form an upper chamber 29 and an intermediate chamber 30, the latter of which is subject to atmos-

pheric pressure by virtue of openings 31 through its wall as seen in Figure 4. The intermediate section 26 and the lower section 27 are separated by a flexible dia-

5 phragm 32, leaving the chamber 33 of the lower section 27 subject to suction from pipe 19 through opening 24 under control of a flat valve 34 which seats on the inner surface of the base of the control box 23

10 around the opening 24.

The upper chamber 29 is in communication with the lower chamber 33 through openings 35 extending through the walls of the control box 23 as particularly seen in

15 Figures 2 and 4, without communication however into the central compartment 30, and the upper compartment 29 is in communication with the lower end of the section 18 of the pressure communicating pipe

20 which is connected to the top of the control box adjacent to one side.

The main control valve 34 is mounted on the lower end of a stem 36 which passes centrally through and is connected to the

25 diaphragm 32 and also has sliding movement through a central aperture of the stationary horizontal partition 28, the upper portion of the stem slidably projecting through a tubular valve stem 37 movable

30 through a central opening of the top of the control box 23. Above the upper end of the hollow valve stem 37, the upper end of the stem 36 has a head 38 engaged by the upper end of a coil spring which surrounds the

35 tubular stem 37 in spaced relation and bears at its lower end upon the lower cross head 39 of a vertically movable frame which also includes an upper cross head 40 and vertical side rods 41 connecting the cross heads.

40 Around its central aperture, the top of the control box 23 has an annular series of openings 42 constituting atmospheric ports, which are controlled by a flat valve 43 seated upwardly against the lower surface of the

45 top of the control box and carried by the lower inner end of the tubular stem 37. The upper end of this stem has an adjustable screw flange as at 44 and receives thereagainst the upper end of a coil spring 44^a depending

50 within the spring 38^a controlling the inner valve stem 36 and, like the latter, bearing at its lower end against the lower cross head 39 of the vertically movable frame before mentioned.

55 The springs 38^a and 44^a are so regulated that the tension on valves 34 and 43 is uniform and light under normal conditions with the vertically movable frame in its lowermost position shown in Figure 2, the

60 valves 34 and 43 being at this time held against their seats with very light pressure so that the former curtails communication between pipe 19 and the control box and thus curtails communication between the

65 reservoir 17 and the player chest 15 without

however cutting off the connection entirely. This pressure communicated from the lower chamber 33 of the control box to the upper chamber 29 through the wall openings is further effected by the entrance of air

70 through the top opening 42 past the valve 43 so that under normal circumstances and with the parts in the normal position shown in Figure 2 in which they are maintained by virtue of springs 38^a and 44^a, there is the

75 least vacuum within the player chest, capable of instant responsive augmentation through the automatic control provided for by my invention.

Extending above the center of the control

80 box 23 with the lower ends of its side extensions 45 connected to the box, is an inverted U-shaped frame, to the upper cross bar 46 of which is connected the upper leaf 47 of a triple bellows, the successive portions of which are indicated at 48, 49 and

85 50, and the lower leaf 51 of which is secured to the upper cross head 40 of the vertically shiftable frame. To the sections 48,

90 49 and 50 of the triple bellows, which sections have geometrically increasing internal areas or air spaces, are extended exhausting conduits 52, 53 and 54, subject to suction in the operation of my invention in order to

95 more or less collapse these bellows, either slowly or speedily for the purpose of raising the vertically adjustable frame to which the lower portion of the bellows is connected, it being obvious that when so collapsed the

100 main valve 34 is raised, permitting a greater area of communication between pipe 19 and chamber 33 and that the supplemental atmospheric valve 43 is also pressed upwardly to more closely cover the top openings 42, thus augmenting the vacuum within the

105 player chest 15. The piano is then playing loudly and if it is desired to soften the tone, release of the triple bellows permits both valve 34 and 43 to return to normal tension of their springs 38^a and 44^a. Air at once

110 enters through openings 42 and at once reduces the pressure in the player chest.

For the purpose of controlling collapsing movement of the triple bellows to secure rapid and slow movements, I extend the conduits 52, 53 and 54, previously mentioned to the lower surface of a vertically apertured valve frame 55, the apertures of which are normally in full communication with upright tubes 56, 57 and 58 through the central series of openings 59 of slide rods 60, 61 and 62 movable in the valve frame across the upper ends of the conduits 55, 56 and 57. These slide rods are connected at their opposite ends by brackets 63 and 64 to the movable leaves of bellows 65 and 66, which movable leaves are engaged by springs 67 and 68 of equal tension so that the slide rods are normally held in the central position shown in Figure 6.

Above the slide rods the suction conduits 56, 57 and 58 are connected for registry with slide rod openings 72, 73 and 74 in a transverse series at one side of their centers and 5 openings 75, 76 and 77 in a second transverse series at the opposite side of their centers, the openings in each series progressing in the same geometrical relation existing between the compartments of the triple bellows, and the openings of one series being substantially greater than those of the other yet smaller than the central series 59, so that when the pneumatic 65 is collapsed, the several slide rods 60, 61 and 62 will be shifted to the right, registering their openings 72, 73 and 74 between the suction conduits 56, 57 and 58 and the upper ends of the tubes 52, 53 and 54, thus subjecting the triple bellows to a somewhat slower collapsing movement than when the openings 59 are registered as in the normal position and yet faster as compared to that permitted when the pneumatic 66 is collapsed and the slide rods openings 75, 76 and 77 of smaller 20 diameters are placed in registering position.

The collapsing of the pneumatics 65 and 66 is controlled through suction pipes 78 and 79 leading from a valved controller 80, this controller being subject to suction 30 through a conduit 81 leading from a source of pressure as for instance the reservoir 17 as seen in Figure 1. The valves of this controller control communication of suction to the suction pipes 78 and 79 and are in turn 35 controlled by valves therein actuated through tubes 82 and 83 leading from the tracker board openings 84 and 85 as seen in Figure 5. Thus when one of the corresponding openings of the note sheet 11 registers 40 with the tracker board opening 84, rush of air into the tube 82 shifts the primary valve of the controller 80 to register the suction pipe 78 with the pressure prevailing in the controller and the pneumatic 65 will thus be 45 collapsed, shifting the slide rods to the position first described above for bringing about a moderately slow increase in tone volume. Likewise when one of the corresponding note sheet openings comes into registry with 50 the tracker board opening 85, a similar action takes place in respect to the suction tube 83 and suction pipe 79 through the controller 80 to collapse the pneumatic 66 and secure a very slow gradual increase in tone 55 volume.

Upon completion of either a gradual or a quick increase in tone volume above the normal, the increased volume may be retained by virtue of the fact that one of the side 60 bars 41 of the vertically shiftable frame previously described, and as particularly seen in Figures 2 and 3, has a transverse recess 88 and passes through an upright bearing tube 89 having a vertical series of trans- 65 versely disposed locking pins 90, each en-

gaged by the free end of a spring wire 91. The series of wires 91 are horizontally disposed as shown in Figure 3 and are secured by a clamp 92 to a supporting upright 93, the extremities of the several wires projecting beyond the tubular bearing 89 and being simultaneously engageable by a releasing plate 94 secured to and shiftable with a collapsible pneumatic 95 which is also supported by the upright 93. With the pneumatic 75 94 in its normal inactive position shown in Figure 2, the several pins 90 are all potentially active. The releasing pneumatic 95 is however controlled, that is collapsed, by virtue of the suction pipe 96 thereof, said 80 suction pipe leading from the controller 80 and in turn controlled by means of a tube 97 leading from a tracker board opening 98, corresponding note sheet openings thus controlling the collapsing of the bellows 95 85 through pipes 96 and 97, so that when the triple bellows is partly or wholly exhausted release of suction on the pneumatic 95 will permit one of the series of pins 90 to shift into the frame rod opening and hold the 90 frame until a further collapse of bellows 95.

The tubes 56, 57 and 58, before described, which control the extent of collapsing of the triple bellows, also extend to the control box 80, as seen in Figures 1 and 5 and are in 95 turn controlled by tracker board tubes 99, 100 and 101 which lead from tracker board openings 102, 103 and 104 for the respective collapse of bellows 48, 49 and 50. Each bellows may thus be independently collapsed, or collapsed along with one or more of the others, depending upon the extent to which it is desired to raise the frame 45.

It is understood of course that the tracker board and note sheet openings controlling 105 accentuation and those controlling the period of sustaining of the accentuation, are separate from and in addition to the ordinary series of 88 note openings.

In Figure 5 I have shown the music sheet 110 perforated at one side in a plurality of succeeding horizontal lines indicated by the letters A to K inclusive and it will be observed that as the first line A passes over the tracker board 10, tracker board openings 102, 103 and 98 will be exposed. Thereupon bellows 95 will be collapsed as well as bellows 48 and 49, collapse of the former withdrawing the pins 90 so that frame 45 can rise under the effect of collapse of bellows 48 and 49. As the line B passes over the tracker board the bellows 48 and 49 will remain collapsed, but tracker board opening 98 is now closed and bellows 95 distends, one of its pins 90 entering the frame recess 88 so as 115 to hold the frame and maintain the increased volume until the bellows 95 is again collapsed such as happens when line C passes over the tracker board, at which the parts resume normal position, the piano then play- 120 125 130

ing extremely soft until line D passes over tracker board 10. At this line D tracker board openings 102, 103, 104 and 98 are exposed so that all three bellows 48, 49 and 50 are collapsed with the collapse of bellows 95 so that the succeeding notes between lines D and E will be struck with extreme loudness until at line E the bellows 95 is again collapsed, permitting bellows 48, 49 and 50 to 10 distend.

From F to K I have shown an arrangement of perforations permitting of a very slow crescendo, line F exposing the tracker board opening 85 which brings about collapse of bellows 66 and thus draws the small openings 75, 76 and 77 into registry with the bellows tubes 52, 53 and 54, so that as this position is maintained from F to K and at G the tracker board openings 102, 103, 104 20 and 98 are exposed, collapsing the bellows 48, 49, 50 and 95, there will be a gradual increase in volume of sound under the control of the restricted bellows collapsing connections until line K is reached when the several parts are permitted to return to normal position. It will be noted that during this entire very gradual crescendo, the bellows 95 is maintained in collapsed position as it would otherwise prevent the desired 30 gradual rise of the frame 45. If a less gradual crescendo were to be produced the perforations from G to K would expose the tracker board opening 84 instead of 85 and thus collapse bellows 65 instead of 66.

35 In a like manner it is quite obvious the degree of loudness as well as its speed may be controlled, and in a similar manner the degree and speed in producing a diminuendo may be controlled. This suffices to show the 40 various combinations which may be brought about in desired or proper interpretation of music of which my invention is capable, and it thus becomes obvious that in addition to the other advantages previously described, I am enabled to obtain sustained accentuation and control the accentuation by means of single note sheet openings instead of elongated slots in the usual note sheet for this purpose. It is furthermore obvious 45 that I provide an arrangement which may be readily installed in connection with practically any type of player action, capable of effective efficient automatic action and which only requires additional tracker board openings with the corresponding openings in the note sheet.

I claim:

60 1. An attachment of the character described for player actions including a controller box having suction connections and atmospheric ports, spring controlled valves normally under moderate tension of their springs for controlling the said suction connection and atmospheric ports, means engageable with and for moving the springs of

said valves whereby to increase the tension on the valves, including suction controlled bellows and note sheet controlled means for exhausting the said bellows.

2. The combination with the valve chest and suction supply means of a pneumatic player action, of a suction control box therebetween, having atmospheric ports, a valve in the box controlling the communication of suction to the valve chest, a second valve in the box controlling the atmospheric ports, springs engaging the said valves and normally holding the same under moderate tension, an adjustable member on which the said springs have bearing and movement of which serves to simultaneously vary the tension of the springs, a bellows connected to and adapted to adjust said spring bearing member, and note sheet controlled suction connections for exhausting said bellows. 70 75 80 85

3. The combination with the valve chest and suction supply means, of a control box therebetween having a valve operating to control the suction supply to the valve chest, and also having an atmospheric port and a valve controlling said port, suction operated means for simultaneously controlling the effective positions of said valves, and note sheet controlled means for controlling the operation of said valve controlling means, including means to vary the speed of operation thereof. 90 95

4. The combination with the valve chest and suction supply means, of valved means interposed therebetween for controlling the supply of suction to the valve chest, a valve controlling communication between the valve chest and the atmosphere, suction actuated means for simultaneously adjusting the valves of said first named means, and note sheet controlled suction connections leading to said valve adjusting means and including means automatically acting to control the volume of suction supplied to the said valve adjusting means. 100 105 110

5. The combination with the valve chest and suction supply means, of means interposed therebetween having valves controlling the supply of suction to the valve chest, suction actuated means for adjusting the valves of said first named means and having suction connections, a controlling valve in said last named suction connections normally in inactive position, having apertures of different areas shiftable in opposite directions into registry with the suction connections to respectively actuate the valve adjusting means slowly and speedily, collapsible pneumatics for moving said last named valve in opposite directions, and note sheet controlled means for independently exhausting said pneumatics. 115 120 125

6. The combination with the valve chest and suction supply means, of means interposed therebetween having adjustable valves 130

for controlling the supply of suction to the valve chest, note sheet controlled means for adjusting the said valves, means to automatically lock the valves in various adjusted positions against both closing and opening movement, and note sheet controlled means for releasing said locking means.

7. The combination with the valve chest and suction supply means, of means interposed therebetween having valves controlling the supply of suction to the valve chest, note sheet controlled means for adjusting said valves including a movable member having a recess, a series of spring actuated pins in the path of movement of said member, each adapted for locking engagement within the recess, and note sheet controlled means simultaneously engageable with the series of pins to shift and hold the latter out of active position.

8. The combination with the valve chest and suction supply means, of means interposed therebetween having valves controlling the supply of suction to the valve chest, note sheet controlled means for adjusting said valves including a movable member having a recess, a series of spring actuated pins in the path of movement of said member, each adapted for locking engagement within the recess, and note sheet controlled means simultaneously engageable with the series of pins to shift and hold the latter out of active position, including a collapsible pneumatic having a plate movable therewith to simultaneously engage the several pins of the series.

9. The combination with the valve chest and suction supply means, of a control box therebetween having a valve controlling the supply of suction to the valve chest and also having atmospheric ports, a valve controlling said atmospheric ports, springs normally under moderate tension, a frame upon a portion of which said springs have bearing, a bellows connected to said frame and collapsible to adjust the latter and increase tension on the springs, note sheet controlled suction connections for exhausting said bellows, means automatically engageable with a portion of the said frame to lock the same in various adjusted positions, and note sheet controlled means for releasing said locking means to permit the frame to return to normal position after suction on the bellows has been cut off.

10. The combination with the valve chest and suction supply means, of valved means interposed therebetween for controlling the supply of suction to the valve chest, suction actuated means for adjusting the valves of

said first named means, means for locking the said adjusting means in various adjusted positions against both closing and opening movement, note sheet controlled suction connections for said adjusting means, and note sheet controlled means for releasing said locking means and holding the same in inactive position.

11. The combination with the valve chest and suction supply means, of a control box therebetween having a valve operating to control the supply of suction to the valve chest and also having an atmospheric port and a valve controlling said port, suction operated means for simultaneously controlling the effective positions of said valves, and note sheet controlled means for controlling the operation of said valve controlling means, including means to vary the speed of operation thereof and also including automatically releasable means to lock the said valve controlling means in various adjusted positions.

12. A pneumatic player action including a valve chest, pressure supply connections for said valve chest, and note sheet controlled means for automatically varying the pressure supplied to said chest, including means for automatically locking the said pressure varying means in various adjusted positions against movement and note sheet controlled means for releasing said locking means.

13. A pneumatic player action including a valve chest, pressure supply connections leading to said valve chest, note sheet controlled means interposed within said connections for automatically varying the pressure supplied to said valve chest, including therein note sheet controlled means for selectively controlling the speed of said pressure varying means, means to automatically lock the pressure varying means in various adjusted positions against movement, and note sheet controlled means for releasing said locking means as described.

14. A pneumatic player action including a valve chest, pressure supply connections leading to said valve chest, note sheet controlled means located in said pressure supply connections for automatically varying the pressure supplied to the valve chest, mechanical locking means for automatically locking the pressure varying means in various adjusted positions against movement, and note sheet controlled suction actuated means for releasing said locking means and for holding the latter in inactive position when desired.

ORMOND EDGAR WALL.
